SANDWICH TOASTER

Herman Schwartz, Long Island City, N. Y.

Application March 22, 1950, Serial No. 8,690

Term of patent 14 years

(Cl. D81—10)

To all whom it may concern:

Be it known that I, Herman Schwartz, a citizen of the United States, residing at Long Island City, New York, have invented a new, original, and ornamental Design for a Sandwich Toaster, of which the following is a specification, reference being had to the accompanying drawing, forming a part hereof.

I claim:

The ornamental design for a sandwich toaster, substantially as shown.

HERMAN SCHWARTZ.
